(57) **CLAIM**

The ornamental design for a tire sealing and inflation device, as shown and described.

DESCRIPTION

Tire sealing and inflation device

1.1 : Perspective view

1.2 : Top view

1.3 : Bottom view

1.4 : Right view

1.5 : Left view

1.6 : Front view

1.7 : Back view

The features shown in broken lines form no part of the claimed design.
